UNITED STATES PATENT OFFICE.

JOHN B. GENTILE, OF MANCHESTER, NEW HAMPSHIRE.

DESIGN FOR A SHOE.

49,605.

Specification for Design.

Patented Sept. 5, 1916.

Application filed May 13, 1916. Serial No. 97,447. Term of patent 7 years.

To all whom it may concern:

Be it known that I, JOHN B. GENTILE, a subject of the King of Italy, residing at Manchester, in the county of Hillsboro and State of New Hampshire, have invented a new, original, and ornamental Design for Shoes, of which the following is a specification, reference being had to the accompanying drawing, forming part thereof.

The figure is a side view of a shoe, showing my new design.

I claim:

The ornamental design for a shoe, as shown.

May 11, 1916.

JOHN B. GENTILE.
